INDICATING SYSTEM FOR OVERDRIVE
CONTROL

Edward M. Claytor, Anderson, Ind., assignor to
General Motors Corporation, Detroit, Mich., a
corporation of Delaware

Application June 6, 1941, Serial No. 396,843

1 Claim. (Cl. 177—311)

This invention relates to means for indicating, by the burning of an electric lamp, the function of electrical apparatus used more particularly on an automobile. Such electrical apparatus may be, for example, the electrical system for controlling the automobile overdrive. In one form of automobile overdrive controlling system it has been the practice to indicate that the system has started to function for the purpose of placing the transmission in overdrive by the burning of a lamp and the establishment of the overdrive when the lamp ceases to burn. For day time driving it is desirable that this lamp be distinctly visible, therefore, a lamp which shows a bright red color has been found satisfactory. However, to some drivers a brilliant colored light is objectionable, especially when driving at night and especially in those systems of overdrive control which provide that the lamp shall burn while driving at moderate and high speeds and shall go out only when the overdrive becomes operative. It is therefore an object of the invention to soften the effect of the brilliant red lamp when driving after dark by mingling with the rays from the red lamp the rays of a lamp of a more subdued color so that the combined effect is a pleasing light rather than an objectionable one. To accomplish this object, I provide a lamp housing for two lamps, one of which gives a brilliant red light which is controlled by the overdrive control system, the other of which gives a soft blue light and is controlled by the lighting switch when actuated into either of its "on" positions. The front wall of the lamp housing facing the driver is provided with a ground glass pane illuminated by the rays from either or both lamps. In the day time the pane will show red to indicate the functioning of the overdrive. At night when the lights are turned on and the vehicle speed is at least moderate and the overdrive control is conditioned so that overdrive may be effected when desired, the pane will show purple. At night when driving at low speeds, or when driving at higher speeds with the overdrive not effective, the pane will show blue.

Further objects and advantages of the present invention will be apparent from the following description, reference being had to the accompanying drawing wherein a preferred embodiment of the present invention is clearly shown.

In the drawing:

The drawing is a wiring diagram of a form of the present invention.

A generator 20 is connected through a reverse current relay 21 and an ammeter 22 and wire

23 with battery 24 which is grounded. Current for ignition purposes is obtained by closing a switch 25 connected with wire 23 and primary 27 of ignition coil 26. The secondary 28 of the ignition coil is connected with the ignition distributor, not shown, and is grounded through the timer 29 with which primary 27 is connected.

The overdrive control system includes a control relay 30 having a core 31 surrounded by 10 magnet coil 32 which when energized attracts an armature 33 carrying a contact 34 engageable with a contact 35. Armature 33 insulatingly supports a resilient contact support 36 carrying a contact 37 normally engaging a contact 38 connected by wire 39 with terminal 40 between primary 27 and timer 29. Magnet coil 32 is connected with armature circuit 33a connected by wire 41 with wire 42 connected with battery 24. The circuit of coil 32 is controlled by three 15 switches in series namely 45, 50 and 55. Switch 45 comprises stationary contacts 43 and 44 normally unbridged by a movable contact 46 held by a spring 47 against a stop 48. Switch 45 is closed when the transmission gear shift lever is moved into high or intermediate position. Switch 50 comprises stationary contacts 51 and 52 normally bridged by a movable contact 53 held in contact making position by a spring 54. The operating member 53a of switch 50 is located in 20 alignment with the accelerator pedal so that, when the pedal is depressed to a position required for rapid acceleration, the switch contact 53 will be separated from the stationary contacts. Switch 55 is a speed responsive switch which 25 may be in the form of a centrifugal switch operated by the engine or in the form of an air vane switch as shown. In the disclosed form the switch 55 comprises a stationary contact 56 normally out of contact with an air vane 57 pivoted 30 at 58 and grounded. Vane 57 is normally urged by a spring 59 against a stop 60. At a certain vehicle speed corresponding to a certain speed of the engine cooling fan 61, a current of air 62 is caused to impinge upon the vane 57 and is sufficient to overcome spring 59 and effect engagement between vane 57 and contact 56. Therefore, relay 30 becomes automatically energized 35 when the transmission gear shift lever is in intermediate high position at a certain vehicle speed such as 25 m. p. h. has been attained. When this occurs armature 33 will be attracted downwardly to separate contacts 37 and 38 and to engage contacts 34 and 35. Battery 24 will 40 then be connected to wires 42, 41, armature 33,

contacts 34 and 35 and wire 65 with a main attracting coil 66 of a solenoid unit 70.

The solenoid 70 comprises a magnetizable cylindrical frame 71 enclosing a magnetizable core 72, the main winding 73 and the auxiliary winding 74. The bottom of the frame 71 and the core 72 are apertured to receive a rod 75 extending through an apertured armature 76, which cooperates with a nut 77 to provide a chamber 78 for housing a spring 79 bearing at its upper end against the nut 77 and its lower end against a collar 80 provided by rod 75. A spring 81 interposed between frame 71 and the flange of nut 77 urges the nut 77 and hence the armature 76 and the rod 75 upwardly, said upward movement being limited by the engagement of nut 77 with a stop 82. The lower end of rod 75 is attached to a sun gear locking pawl 90 slideable between ways 91 and 92 provided by a frame 93 of the overdrive transmission housing. Pawl 90 is adapted to be received by notches 94a provided by a locking ring 94 connected with the overdrive sun gear 95. A blocker plate 96 is frictionally connected with locking ring 94 and its rotation in either direction is limited by the lugs 97 and 98 thereof engaging respectively with the ways 91 and 92.

As explained heretofore, relay 30 is energized in response to attainment of a certain vehicle speed provided switch 45 has been closed by movement of the gear shift lever into an intermediate or high position. The closing of contacts 34 and 35 of relay 30 cause magnet coil 73 of solenoid 70 to be connected with the battery to cause armature 76 to move downwardly and the pawl rod 75 to move downwardly under the action of spring 79. However, the pawl 90 will not immediately go into engagement with the sun gear lock ring 94, but will engage one of the surfaces 97a or 98a of the blocker 96. To go into overdrive, the driver must allow the engine speed to drop a certain percentage below corresponding vehicle speed in order to obtain a movement of the blocker 96 such that its notch 99 will be located in alignment with the pawl 90; and then the pawl 90 will engage the sun gear locking ring 94 in order to prevent rotation of the sun gear 95 and the transmission will be overdrive as is well understood by those skilled in this art. When the pawl 90 has engaged the ring 94 the flange of nut 77 will have engaged a resilient contact support 100 to move a contact 101 out of engagement with a contact 102 thereby disconnecting the main attracting coil 73. The armature 76 however will be held in attracted position by the auxiliary or holding coil 74 which is connected by the battery through wire 105 connected with wire 65 through magnet coil 111 of time relay 110.

Relay 110 comprises a core 112 surrounded by the coil 111 and having a chromium plated pole face 113 adapted to be engaged by the armature 114 when attracted downwardly to bring contact 115 into engagement with contact 116. Contact 116 is connected by wire 117 with the support 36 of relay 30 which carries contact 37. Armature 114 is connected by wire 118 with a terminal 119 connected with resilient contact carrier 120 carrying a contact 121 adapted to engage grounded contact 122. Contact carrier 120 carries a non-conducting button 123 engageable with the upper end of rod 75. Short circuited coil 111a retards decay of the flux of the relay 110. When the contacts 37 and 38 of relay 30, contacts 115 and 116 of relay 110 and contacts 121 and 122 of sole-

noid unit 70 are all closed at the same time, there is provided the following ignition grounding circuit: terminal 40, wire 39, contact 38, contact 37, support 36, wire 117, contact 116, contact 115, 5 armature 114, wire 118, terminal 119, carrier 120, contact 121, contact 122. This grounding circuit is established for the purpose of rendering the engine momentarily inoperative in order to facilitate retraction of the sun gear locking pawl 90 when it is desired to come out of overdrive.

To come out of overdrive the driver depresses the accelerator pedal for the purpose of obtaining a rapid acceleration thereby opens switch 50 and interrupting the circuit of relay coil 32. 15 Relay 30 opens quickly to cause contacts 34 and 35 to be disconnected whereupon magnet coil 74 of solenoid 70 and magnet coil 111 of relay 110 are disconnected from the battery. Since relay 110 is a time lag relay there will be an appreciable 20 time, for example one-tenth second, between the closing of contacts 37 and 38 and the opening of contacts 115 and 116. During this period the ignition is inoperative in order to relieve pressure on pawl 90 and thus to facilitate the retraction 25 of pawl 90 through the action of spring 81 of solenoid unit 70.

The functioning of relay 30 to condition the system for going into overdrive is visibly indicated to the driver by the burning of lamp 121 in signalling unit 120 which comprises a housing 122 for supporting the detachable socket 123 for the lamp 121 and a detachable socket 124 for a lamp 125. Lamp 121 is connected by wire 130, contact 131, 132 of solenoid 70 and wire 133 and wire 65 which is connected with the battery 24 when the contacts 34 and 35 of relay 30 are closed. Lamp 124 gives out brilliant red rays which are projected upon a ground glass pane 134 in the front wall of housing 126 facing the driver. A brilliant red color is distinctly visible to the driver in the day time. When driving at night this brilliant red color may be objectionable. Therefore its effect is softened by the burning of lamp 129 which is turned on whenever any of the other automobile lamps are turned on. The lamp 129 gives out soft blue rays which mingle with the red lamp 124 to produce a purple hue upon the ground glass pane 134.

Lamp 125 is connected with a conventional automobile lighting circuit which will now be described. Wire 42 connected with battery 24 is connected by fuses 140 and 141 with contacts 142 and 143 respectively. Contact 142 is connected by strap 144 with contact 145. The main lighting switch comprises two movable contacts of triangular formation 146 and 147 insulated from each other and connected with a common operating member 148. When the contacts 146 and 147 are in the parking positions 146' and 147' indicated by dot dash lines, the following circuits are established: through wire 149 and wire 150 to tail lamp 151 and lamp 125 and a circuit through wires 152 and 153 to parking lamps 154 and 155. When the contacts 146 and 147 are in the driving positions indicated in full lines, the following circuits are established: the circuit including wire 160, the dimmer switch 161 for selectively connecting the bright filament 162 or the dim or depressed beam filament 163 of head lamp 164 with wire 166; and the circuit including wire 170 and a dimmer switch 171 for selectively connecting the main filament 172 and the dim or depressed beam 173 of head lamp 174 with wire 170. The movable contacts 161a and 171a of dimmer switches 161 and 171 respectively

are insulated from each other but are actuated by a common operating member 180.

From the foregoing description of the construction and mode of operation of the system embodying my invention, it is apparent that when driving in the day time, with the lamps turned off, (off positions of switch contacts 146 and 147 are not shown) no light will be visible at the pane 126 of signal unit 125 until the driver has pressed the transmission in intermediate or high and has attained a predetermined speed, for example, 25 M. P. H. When this has happened relay 30 will be energized and that fact will be indicated to the driver by the burning of lamp 124 which will cause a brilliant red spot to appear on the ground glass 134. The red spot will continue until the driver allows the engine to decelerate a certain percentage below vehicle speed whereupon the blocker 96 moves so as to allow the pawl 90 to move into locking engagement with the sun gear then the lamp 124 will cease to burn. The disappearance of the red spot from the pane 134 will indicate to the driver that the transmission is in overdrive. When the driver depresses the accelerator pedal sufficiently to cause the transmission to come out of overdrive by the opening of switch 50 and then no light will burn but when the accelerator pedal is released the lamp 124 will burn again to indicate that the relay 30 is operative to condition the system for going into overdrive again if the driver so desires.

When parking at night the main lighting switch is actuated so that its contacts are in positions 146' and 147' the head lamps are off and the parking lamp, tail lamp and lamp 125 are on. The burning of lamp 129 causes a blue spot to appear on the ground glass 134 to indicate to the driver that the parking lamps are on when he leaves the car. When the driver starts to drive away the blue light continues to burn although he has turned off the parking lamps and has turned on the head lamps. After the driver has shifted the transmission into intermediate or high condition and has attained a speed of 25 M. P. H., the lamp 124 will also burn.

The rays of lamps 124 and 129 will combine and a purple spot will appear on the ground glass pane 134 to indicate to the driver that the overdrive control system has started to function for conditioning the sun gear locking pawl for going into overdrive which will occur provided the driver permits the engine to decelerate a certain percentage below the corresponding vehicle speed. When this happens the pawl 90 will move into engagement with the sun gear locking ring 94 and the contacts 131 and 132 will open so that lamp 124 will cease to burn. The color will change from purple to blue on ground glass 134 to indicate to the driver that the car is in overdrive.

In this way I have provided for the indication of the status of the overdrive control system by a visible signal which is distinctly visible in the day time and one which is modified by the use of the lights by night so as not to be so objectionable to the driver who must look into this signal when driving at night.

While the embodiment of the present invention as herein disclosed, constitutes a preferred form, it is to be understood that other forms might be adopted, all coming within the scope of the claim which follows.

What is claimed is as follows:

A visual indicator for use on automobiles comprising a lamp housing providing a translucent screen to be illuminated, a lamp within the housing for projecting upon the screen a brilliant color readily observed in the day-time, another lamp within the housing for projecting upon the screen a light of subdued color whereby, when both lamps are burning at night, the screen will show a combined color much less brilliant than that given by the first lamp alone, which combined color may be observed at night with pleasing effect, means operable in response to a condition of the automobile for causing the first lamp to burn, and means responsive to the turning-on of the lamps of the automobile for causing the second-mentioned lamp to burn.
